(57) **CLAIM**

We claim the ornamental design of a wine rack, as shown and described.

DESCRIPTION

FIG. 1 is a front right perspective view of the wine rack of the present invention;

FIG. 2 is a left side elevation view thereof;

FIG. 3 is a front elevation view thereof;

FIG. 4 is a rear elevation view thereof;

FIG. 5 is a top orthographic view thereof;

FIG. 6 is a bottom orthographic view thereof; and,

FIG. 7 is an illustration of a possible use scenario thereof, wherein broken line representations of bottles form no part of the claimed design.

The right side elevation is a mirror image of the left side elevation.
